[57] CLAIM

The ornamental design for an anchor, as shown and described.

DESCRIPTION

FIG. 1 is a perspective view of a first embodiment of the anchor showing my new design;

FIG. 2 is an elevational view of the anchor of FIG. 1;
FIG. 3 is an elevational view of the anchor of FIG. 2 rotated 45° in either direction;

FIG. 4 is an elevation view of the anchor of FIG. 2 rotated 90° in either direction;

FIG. 5 is a top plan view of the anchor of FIG. 1;

FIG. 6 is a bottom plan view of the anchor of FIG. 1;

FIG. 7 is a perspective view of a second embodiment of the anchor showing my new design;

FIG. 8 is an elevational view of the anchor of FIG. 6;

FIG. 9 is an elevational view of the anchor of FIG. 8 rotated 45° in either direction;

FIG. 10 is an elevational view of the anchor of FIG. 8 rotated 90° in either direction;

FIG. 11 is a top plan view of the anchor of FIG. 7, the bottom plan view being the same as that shown in FIG. 6;

FIG. 12 is a perspective view of a third embodiment of the anchor showing my new design;

FIG. 13 is an elevational view of the anchor of FIG. 12;

FIG. 14 is an elevational view of the anchor of FIG. 13 rotated 45° in either direction;

FIG. 15 is an elevational view of the anchor of FIG. 13 rotated 90° in either direction; and,

FIG. 16 is a top plan view of the anchor of FIG. 12, the bottom plan view being the same as that shown in FIG. 6.
